Paul Fantel, Asbury Park, N. J.

Application January 11, 1949, Serial No. 193

Term of patent 7 years

(Cl. D58—8)

To all whom it may concern:

Be it known that I, Paul Fantel, a citizen of the United States, residing in Asbury Park, New Jersey, have invented a new, original, and ornamental Design for a Bottle, of which the following is a specification, reference being had to the accompanying drawing, forming part thereof.

Fig. 1 is an elevational view of a bottle showing my new design;

Fig. 2 is a bottom plan view; and

Fig. 3 is a top plan view.

I claim:

The ornamental design for a bottle, as shown.

PAUL FANTEL.
